PRESSURE-REDUCING VALVE FOR AIR-FEED DRILLS.

1,086,413.

Specification of Letters Patent.

Patented Feb. 10, 1914.

Application filed March 20, 1912. Serial No. 685,106.

To all whom it may concern:

Be it known that we, ALBERT H. TAYLOR and LEWIS C. BAYLES, citizens of the United States, residing at Easton, in the county of 5 Northampton and State of Pennsylvania, have invented certain new and useful Improvements in Pressure-Reducing Valves for Air-Fee Drills, of which the following is a specification.

This invention relates to a pressure reducing device for use with air feed fluid operated drills. Drills of this kind consist broadly speaking of a drill fed toward its work by the pressure of the air against a piston in a cylinder in line with the drill, the air pressure being taken direct from the supply pipe operating the drill. In such a machine the force with which the drill is fed is dependent on the diameter of the piston 10 ton in the feeding cylinder. If this piston is sufficiently large to properly support the drill when boring a vertical "up hole", as in the roof of a stope, there will be a large excess pressure when boring a horizontal or 15 "flat" hole, and a still greater excess pressure in boring a "down hole". Also if the same direction is maintained and the air pressure varied the drill will be fed forward with different force. On account of this difference in feeding power required, it is necessary for a given type of drill to build 20 different sizes of air feeds, and to supply various different sizes for various conditions.

The object of this invention is to provide 25 a valve between the main feed supply and the air feed cylinder which can be adjusted to reduce the pressure in the air feed for different cylinder conditions, so that if a drill is furnished with cylinder sufficiently 30 large to meet the most difficult case, the feed can be adjusted down to adapt it to various less stringent conditions.

We are aware that reducing valves are known where the pressure of the fluid delivered to the air feed is varied with relation to the fluid furnished to the tool. We do not contemplate a device of this kind however. In the present device, the valve will maintain a given pressure in the air feed cylinder regardless of the pressure in the air supply, providing this exceeds the pressure for which the valve is set.

With this object in view, we have devised a valve a practical embodiment of which is

shown in the accompanying drawings in which—

Figure 1 is an elevation of the complete drill and air feed showing the position of the valve. Fig. 2 is a vertical section through the valve on the line II—II of Fig. 60 4. Fig. 3 is a section through the line III—III of Fig. 2. Fig. 4 is a plan of the valve section looking from the air feed cylinder side.

In the embodiment shown in the drawings, the complete drilling machine comprises a separate disk like valve section 1 which is of such a form as to fit and be secured by bolts 2 through bolt holes 3 between the head block 4 of a usual form of drill provided with a usual air inlet 5, and the head block 6 of a usual form of air feed cylinder 6^a in which slides a piston rod 7, the head blocks 4 and 6 being of such a form that they fit together and can be secured together 70 without the intervention of the valve section 1 containing the pressure reducing valve, if a pressure reducing valve is not desired.

The valve chest 1 is pierced in a diametral direction by a cylindrical bore 8 with a 75 slightly contracted portion in which is seated the spool valve 9 so that it can slide freely in either direction. The spool valve 9 has a contracted portion 10 which is always in communication with a port 11, 80 which is in free communication with the port 12 leading from the inlet 5. From the other side of the bore at such a point that it will be closed by slight movement of the spool valve 9 is a port 13 leading into the 85 air feed cylinder 6^a. A second port 14 from the feed cylinder leads to the back of the valve to a clearance which is maintained at all times by a boss 15 on a nut 16, which is threaded into the end of valve bore 8. On 90 the other side of the spool valve is a spring 17 which presses the valve toward the nut 16, and is adjustably compressed by a plunger 18 provided with lugs 19 sliding in longitudinal grooves in the bore and actuated 100 by a threaded spindle 20, mounted to turn freely in a nut 21, threaded in the end of the valve bore. The spindle is provided on its outer end with a thumb screw 22. A vent port 23 lead from the bore 8 just inside the nut 21 to the atmosphere.

The operation of the valve is as follows: Suppose the valve spool to be in the posi-

tion shown in Fig. 2 which will be the case when the air pressure is not on in the drill. When the air is now turned on, it will pass through ports 12, 11, 13 into the air feed cylinder. Since the clearance back of the valve spool is open to the feed cylinder pressure through port 14, and the bore 8 on the other side of the spool is open to the atmosphere through port 23, there will be a fluid pressure on the back of the spool tending to close the port 13, which pressure is balanced by the pressure of the spring 17 on the other side of the spool valve. When the pressure on the back of the spool reaches a certain point it will overcome the pressure of the spring and close the port 13. This point of closing is determined by the compression of the spring 17 which can be changed by adjusting the position of plunger 18. It will be seen, therefore, that the spring 17 can be adjusted for any desired pressure in the air feed cylinder and this will be maintained as long as the pressure in the drill is above this desired pressure.

It is to be understood that the present disclosure shows only one embodiment and

changed and modified forms of the device are considered within the spirit and scope of our invention as expressed in the claims.

What we claim is:

1. In combination, a fluid operated drill having a head block, an air feed cylinder for said drill having a head block adapted to fit said drill head block, and a pressure reducing valve section fitting between said head blocks and removably secured thereto.

2. As an article of manufacture, a valve chest of disk like form containing a pressure reducing valve, said valve chest having bolt holes therethrough and adapted to be secured between the drill and air feed cylinders of an air feed drill.

3. As an article of manufacture, a valve chest of disk like form containing a pressure reducing valve, said valve chest being adapted to be secured between the drill and air feed cylinders of an air feed drill.
